VALVE

Frank H. Cross, Cleveland, Ohio

Application July 27, 1935, Serial No. 33,538

3 Claims. (Cl. 50—12)

This invention relates to valves and particularly to valves for controlling the pressure of fluids.

An object of the invention is to provide an improved valve which will control the pressures of fluids delivered therefrom.

Another object is to provide an improved valve in which the pressure of fluids can be controlled within very narrow limits.

Another object is to provide an improved valve which will control the pressure of fluids under conditions of relatively high pressure and temperature.

Another object is to provide an improved valve which may be easily adjusted for any desired pressure.

Another object is to provide an improved valve which will be simple in construction.

Another object is to provide an improved valve which will be simply adjusted.

Another object is to provide an improved valve which will have few moving parts.

Another object is to provide an improved valve in which no parts must move through packing.

Another object is to provide an improved valve which may be used to control large sized passageways for the passage of fluids.

Other objects will hereinafter appear.

The invention will be better understood from the description of one practical embodiment thereof illustrated in the accompanying drawing, in which:

Figure 1 is a side elevational view, parts being broken away and shown in section, of an improved pressure reducing valve embodying my invention; and

Figure 2 is a horizontal sectional view taken on the line II—II of Figure 1.

The valve illustrated comprises a casing, indicated generally at 1, and having two projecting tubular extensions shown as an internally threaded extension 2, constituting the intake side of the valve, and an oppositely disposed internally threaded tubular extension 3, which constitutes the exhaust side thereof, these extensions being adapted to be engaged by pipes of conduits, such as comprise a steam line or the like, and which supply fluid to the valve at a pressure as great or greater than that desired to be passed from the valve to apparatus which utilizes the fluid.

In alignment with extension 2, and forming a continuation thereof, is a closed-ended tubular projection 4, pierced by two vertically aligned apertures 5 and 6, in which is positioned a valve member consisting of upper and lower heads 7 and 8, respectively, connected by peripherally arranged ribs 9 which are united at their top into two projecting lugs 10 which constitute, in effect, a clevice by which the valve may be connected to its actuating mechanism.

The heads 7 and 8 substantially fill the apertures or orifices 5 and 6, respectively, when in their uppermost position, while when the valve is in its lowermost position, as indicated in Figure 1, head 7 is positioned substantially midway between the orifices, and head 8 is in a position substantially below the lower orifice.

Integrally formed with the casing is an upwardly extending flaring flange 11 terminating in a horizontal marginal flange 12. Supported upon the latter is a top or ring 13 having a depending circular flange portion 14 provided with an inwardly extending flange 15. Threaded within the depending flange is a ring 16 having a depending flange 17 in alignment with flange 15 and an outwardly extending flange 18 overlying ring 13.

A gasket or packing ring 19 is positioned between flange 12 and ring 13.

Received in the annular recess formed between flanges 15 and 17 is a centrally apertured disc-like plate 20 and clamped between this plate and these flanges are the outwardly extending ends of two corrugated metallic bellows members 21 and 22.

Within bellows 22 is a vertically extending rod 25 comprising a main enlarged body portion 23 and a reduced threaded extension 24 which passes through a central perforation in the head of bellows 22. A washer 25 overlies the edge of the bellows at this point and is caused to clamp the same tightly upon the end of body portion 23 by a nut 26.

The lower end of the body portion 23 has an axially extending reduced threaded section or stud 27 which passes through the central perforation 35 in disc 20.

Threaded upon this stud is a second rod comprising an enlarged body portion 28 and a smaller internally and externally threaded portion 29 passing through a central perforation in the head 40 of bellows 21.

The bellows about this perforation is clamped against the end of the enlarged body portion 28 by a washer 30 bearing upon it and clamped against it by a nut 31.

Engaging the internal thread or extension 29 is the threaded end of a small rod 32 having an apertured end received between lugs 10 and connected by a pin 33 fastened in position as by a split pin 34.

Supported upon flange 13 is a dome-shaped cover 35 having a marginal flange 36 which overlies both flanges 12 and 13, the flanges 12, 13, and 36 all being clamped together by bolts 37.

A copper plate 38 extends along the upper surface of ring 13 having its edge surrounding its central perforation received between ring 13 and flange 18, and its outer edge between ring 13 and flange 36.

A copper liner 39, conforming closely to the

interior of the dome 35, also has its edge received between ring 13 and flange 36, so that tightening the bolts 37 seals flanges 12, 13 and 36 together by pressing gasket 19, copper plate 38, and the edge of liner 39 between them.

Similarly, tightening the ring 16 seals the edges of both bellows between flanges 15 and 17 and disc 20.

A tubular fitting 40 passes through the wall 10 of dome 35 and is connected by a stop cock 41 to a source of air under pressure, by which air may be admitted to or permitted to escape from the space within the dome.

A similar fitting 42 penetrates the wall of 15 the dome 35 and connects the interior thereof with a gage 43, which indicates the pressure of the air within the dome.

The operation of the device is as follows:

Fluid, such as steam under relatively high 20 pressure, is admitted through extension 1 into the chamber within part 4 and passes through ports 5 and 6 at the rate determined by the position of heads 7 and 8. The pressure beyond the ports 5 and 6 is, of course, lower than the 25 pressure supplied to extension 2, and depends upon the rate at which the fluid is permitted to pass through these ports.

This reduced pressure extends throughout the 30 space within casing 1 and is exerted upon the exterior of bellows 21.

At the same time, any air pressure which has been supplied to the space within dome 35, is 35 exerted upon bellows 22. As long as the pressure upon bellows 22 exceeds that upon bellows 21, the valve remains in its lowermost position, as shown, permitting the maximum amount of fluid to pass through ports 5 and 6.

As soon as pressure on bellows 21 exceeds that on bellows 22, the former is to some degree 40 collapsed and the latter extended by the same amount, this action raising the valve and bringing the heads nearer to their port closing positions, and thus reducing the rate by which fluid may pass through them.

If the pressure within flange 11 continues to rise, bellows 21 is still further collapsed and the 45 ports correspondingly further closed, this continuing until the pressure within chamber 11 drops sufficiently for the air pressure on bellows 50 22 to again depress the valve member.

The adjacent end of body portions 23 and 28 of the rods limit the degree to which the bellows 55 may be collapsed by abutting the sides of disc 20, and so prevent damage to the bellows even when subjected to abnormal pressures.

It will be observed that both pressures are applied to the exterior of the bellows, and the space within both of them is sealed against entrance of either the fluid from chamber 11 or 60 air from dome 35, and in this manner distortion strains from the inside of the bellows are prevented.

It will be apparent that the valve will operate at pressures corresponding to the readings of gage 43 only when the exterior dimensions of 65 both bellows are the same.

If the dimensions of these bellows differ, the operating pressure will be at a ratio to the gage pressure corresponding to the ratio of the cross-sectional areas of both bellows. In other words, 70 if the area of bellows 22 is twice that of bellows

21, the pressure at which the valve operates will be twice that at the gage 43. Of course, the gage can be easily calibrated to indicate what the pressure on bellows 21 need be to cause the device to function.

The valve may be readily adjusted for any operating pressure by varying the pressure of the air within the dome. If set for a certain pressure when the parts are cold and later these become heated, it will be apparent that the air pressure 10 may rise slightly and may be readily reduced by means of the stop cock 41 until the gage again indicates the pressure at which it is desired the apparatus shall function.

The means for limiting the motion of the bellows are all enclosed and protected from the corrosive or other deteriorating influence of the fluid passing through the line, as well as from the air.

It will also be apparent that there are no moving 20 parts in frictional contact, other than the sides of the valve member passing through the ports 5 and 6, and that the valve is both balanced and so suspended that neither fluid pressure nor weight causes it to bear against the sides of the 25 ports. Hence, the effects of friction are substantially eliminated.

The bellows themselves may, to an extent, act 30 as opposed springs in returning the parts to their intermediate position with the ports half open. A very sensitive control device is thus obtained.

While I have described the illustrated embodiment of my invention in some particularity, obviously many other embodiments, variations and modifications will readily occur to those skilled in the art to which my invention appertains, and I therefore do not limit myself to the precise details shown and described, but claim as my invention all embodiments, variations and modifications coming within the scope 40 of the appended claims.

I claim:

1. Two generally cupped shaped bellows having their open ends adjacent each other, a centrally perforated disc-like plate between said 45 bellows, means sealing the edges of said bellows to the sides of said plate, a rigid bar extending through the perforation of the plate and clamped and sealed to both bellows, said bar having projections arranged to contact said plate and spaced 50 apart a distance greater than the thickness of the plate.

2. Two generally cup-shaped bellows each having a closed head and relatively flexible and resilient sides, means sealing the open ends of the 55 bellows together so that the space within both is hermetically sealed and intercommunicating, and a rigid connector positively fastened to the heads of both bellows and connecting them to an element to be actuated.

3. Two generally cup-shaped bellows each having a closed head and relatively flexible and resilient sides, means sealing the open ends of the bellows together so that the space within both is hermetically sealed and intercommunicating, 65 and a rigid connector positively fastened to the heads of both bellows and connecting them to an element to be actuated, and means exposing the exterior of each bellows to a different fluid under pressure.

FRANK H. CROSS.
